HUGH H. MCKENNA, OF LOS ANGELES, CALIFORNIA, ASSIGNOR, BY MESNE ASSIGNMENTS,
TO WONDERFUL DEVELOPMENT COMPANY, A CORPORATION OF NEVADA

DRY AIR SEPARATOR

Application filed November 29, 1927. Serial No. 236,439.

This invention relates to the classifying of mineral particles and consists of a method and apparatus by which classification of the mineral particles is accomplished mainly by controlled air currents.

It is an object of this invention to provide a classifier which is adapted for classifying minerals where the specific weight of the minerals is near that of its gangue.

Another object of the invention is to provide an apparatus in which two or more minerals having substantially the same specific gravity may be separated from its gangue, being collected in separate receptacles.

A further object of the invention is to provide an apparatus in which the mineral is first cleaned and then separated by the action of air currents.

A further object of the invention is to provide an apparatus which has a collection chamber which may be set to collect the mineral of any specific gravity desired.

The invention includes a main separator which has a screen through which the mineral particles are drawn by air currents. Sometimes during the operation of the separator this screen will clog, and when a clogging occurs the efficiency will be greatly reduced.

It is one of the objects of this invention to provide an apparatus in which the screen when it becomes clogged will be automatically cleaned.

It is one of the objects of the invention to provide a method of separating mineral particles from its gangue, in which method the separation is accomplished by controlled air currents.

Other objects and advantages will appear in the following description.

The invention may be best understood by reference to the accompanying diagrammatic drawings in which:

Fig. 1 is an elevational view, partly sectioned, of the apparatus of my invention.

Fig. 2 is a section taken on the line 2—2 of Fig. 1.

Fig. 3 is a section taken on the line 3—3 of Fig. 1.

Fig. 4 is a section taken on the line 4—4 of Fig. 1.

Fig. 5 is a section taken on the line 5—5 of Fig. 1.

Referring to the drawings in detail, the 55 numeral 11 represents a shell, the upper end of which is conical, as indicated at 12, and is provided with an air inlet conduit 13. The lower end of the shell 11 is conical at 15 and has a gangue discharge 16. The ground material which consists of the mineral and its gangue is introduced into the upper part of the shell 11 by means of an inlet 18.

Supported in the upper part of the shell 11 is a breaking device 19 which checks the 65 fall of the comminuted material, scatters any lumps which may be present, and distributes the material evenly through the casing. This breaking device 19 consists of an upper conical screen 20 and a lower conical screen 21, 70 these screens being placed with their bases together. The upper screen 20 is preferably about 70 mesh and the lower screen is preferably about 90 mesh. The lower part of the lower conical screen 21 is provided with an 75 opening 23 through which a nozzle 24 is extended. The upper part of the nozzle 24 is situated in a space 25 in the breaking device 19 and has branch pipes 26 connected thereto. These branch pipes extend radially outward 80 at an angle of ninety degrees from each other to the exterior of the shell 11 where they are joined to a manifold 28. The manifold 28 has an inlet 29, the size of which is controlled by a damper 30.

Situated in the shell 11 below the breaking device 19 is a classifying device 32. This classifying device 32 includes an upper conical screen 33 which is preferably from 80 to 100 mesh. The apex of this conical screen 33 90 may extend into the lower end of the nozzle 24 if desired. The lower part of the classifying device 32 is in the form of a conical member 34 which is provided with screened openings 35. The interior 36 of the classifying device 32 is connected to a suction conduit 38 which extends to the exterior of the shell 11, as shown. Surrounding the conical member 34 is a frusto-conical baffle 39 which provides an annular confined space 40 around the coni- 100

cal member 34. Connected to this annular confined space 40 is a conduit 41 which extends to the exterior of the shell 11. The conduit 41, as shown, is connected to the conduit 38, and the conduit 38 is provided with a suction blower 42 which places a suction on the interior of the shell 11.

When the blower is in operation, air is drawn into the shell 11 through the conduit 13 and through the nozzle 24. Air is also drawn in through openings 44 and 45 in the shell 11 which are controlled by dampers 46 and 47 respectively. The openings 44 and 45 are so regulated and the air is drawn into the shell 11 in such a manner that there is a violent agitation in an agitation chamber 48 provided by the shell 11 between the breaking device 19 and the classifying device 32.

The conduit 38 is provided with an automatic relief valve 50 which is placed at the end of a pipe 51. This relief valve is pivoted at 52 and is provided with a weight 53 which normally holds it in closed position. When the classifying device 32 becomes clogged, the suction in the conduit 38 is increased and the relief valve is swung into the position indicated by dotted lines 54. This permits a sudden inrush of air which flows upward through the interior 36, blowing any material from the screen 33.

The conduit 41 is provided with a trap 56 in which mineral particles may be collected. This trap 56 has a baffle 57 in the interior around which the flow of air carrying the particles must pass. The upper part of the trap is provided with openings 58 which are controlled by a damper 59. The collected material may be removed from the trap through a lower valve control spout 60.

The conduit 38, between the point where the conduit 41 attaches to it and the point where the suction blower 42 is located, is provided with a plurality of traps 62 and 63. Each of these traps is connected to the conduit 38 by a short tube 64. The traps provide closed collection chambers 65 into which the mineral particles may fall. The upper part of each trap is provided with openings 66 which are controlled by a damper 67. Collected material may be withdrawn through a lower valve control spout 69. The tube 64 is provided with suitable baffles 70 which prevent agitation in the chamber 65 of each trap.

The operation of the invention, just described, is substantially as follows:

The blower is set into operation so as to provide air currents inside the shell 11 which will be described in connection with the passage of the material through the apparatus. The material from which the mineral is to be obtained is introduced through the inlet 18. This material is crushed so that it is below 200 mesh. The material falls downward onto the breaking device 19. Almost all of

the material will pass through the upper screen 20, the space 25, and the lower screen 21. Any particles which are larger than 200 mesh are carried through the annular passage between the shell and the upper screen 20, as indicated by arrows 72. These particles are usually heavy enough so that when they reach a point at the largest diameter of the breaking device 19 they fall straight downward through the agitation chamber 48 70

and outward through the gangue discharge 16. The material passing through the breaking device 19 is screened and divided so that none of it is lumped together. This screened material drops into the agitation chamber 48 75

where violent agitation is taking place, as indicated by arrows 71, due to the confluence of the currents of air entering the agitation chamber from the nozzle 24 and the openings 44 and 45. This violent agitation has the 80

effect of thoroughly cleaning the mineral particles of the gangue particles. The gangue particles seem to move to the outer part of the shell 11 and fall downward through the gangue discharge 16. The 85

mineral and some of the fine gangue particles and silt move inward toward the conical screen 33 of the classifying device 32, and a greater portion of the mineral particles are drawn through the screen 33 by the suction 90

placed on the interior 36 by the blower 42. It is the heavier particles of mineral which pass through the screen 33. At this time a stream of air is being drawn 95

inward through the nozzle 24. This stream of air passes downward, as indicated by arrows 73, along the surface of the screen 33 and tends to wash the light particles of gangue and the small particles of mineral from the screen 33. These particles pass 100

downward around the largest diameter of the classifying device 32 and meet in an upflow of air which is being drawn inward through the gangue discharge 16 due to the action of the blower 42. This has the effect of causing 105

the light particles of gangue and small particles of mineral to pass into the confined space 40 provided by the chamber 39. Any heavy particles of gangue which may be present are 110

too heavy to be affected by the upflow of air through the gangue discharge 16 and will therefore pass downward and outward, as indicated by the arrows 74. The suction in the interior 36 of the classifying device 32 draws 115

most of the mineral particles of the material in the closed chamber 40 into the interior of 36 of the classifying device 32. This mineral passes outward through the conduit 38. The material which is not drawn through the screens 35 is drawn through the conduit 41. 120

The current of air flowing through the conduit 38 carries the gangue particles therealong until the first trap 62 is reached. The operation of the traps is substantially the same and comprises an important part of the 125

130

invention. When the damper 67 is closed, all of the mineral particles may drop into the collection chamber. This deposition is facilitated by the upward bend in the conduit 5 above the opening of the trap, since the inertia of the particles tends to carry them in a straight line and therefore out of the main current of the air stream. Since the air current is created due to the lowering of the pressure in the conduit by the blower 42 the pressure in the conduit above the trap is less than atmospheric pressure. It will be seen, therefore, that when the damper 67 is operated to admit air through the openings 66 this air will pass upwardly into the conduit through the material falling into the collection chamber, and prevent the deposition of the lighter particles. Accordingly, if the openings 66 are closed, a large range of mineral particles will be collected, and if the openings 66 are open, a narrow range of mineral particles will be collected; that is, only the heaviest particles will be collected. As the material passes over the first trap 62, the heaviest part 25 of the mineral particles may be removed, and as the material passes over the second trap 63, the lightest part of the mineral particles may be removed. Any silt or small gangue particles will pass with the current of air through 30 the blower 42.

The trap 56 operates in substantially the same manner as the traps 62 and 63, and the mineral particles deposit according to the amount of air introduced into the trap 56 35 through the openings 58. As the material clogs in the classifying device 32, the vacuum in the conduit 38 and in the interior 36 increases to the extent that the relief valve 58 is moved into the position shown by dotted lines 54. This allows an increase of air which reduces the vacuum. This flow of air will pass upward into the interior 36 and tend to flow outward through the screen 33. This forces the clogging particles from the screen. The relief valve 50 will immediately return 45 to proper closing position and normal operation of the apparatus will continue.

The present invention is useful for separating metallic or non-metallic minerals 50 from their gangue. The apparatus shown may be regulated to suit any material by controlling the air currents in the shell 11 and by controlling the vacuum in the traps 56, 62 and 63. If desired, the air which is 55 drawn into the shell 11 through the conduit 13 and the nozzle 24 may be heated air so that no moisture may be absorbed by the comminuted material, which would tend to interfere with the cleaning action in the agitation chamber 48 and in the classification of the mineral.

The lower screens 35 of the classifying device 32 are used only when the material to be classified is of a light specific gravity. 60 When the mineral is of a heavy specific grav-

ity it is found that these screens 35 are not necessary.

As previously explained, this invention is useful for separating two or more products from the same gangue. If the products are 70 of different specific gravities, the traps 56, 62 and 63 may be adjusted so that the particles may be separated according to their weights. It often occurs that a gangue will carry two minerals which are of substantially 75 the same specific gravity. In my invention the minerals of the same specific gravity may be collected in the different traps even though their weights are substantially the same. The reason for this is that the fracture of different minerals differs so that some minerals provide larger exposed surfaces. The air currents act differently upon the minerals according to the exposed surfaces. Although I cannot exactly explain just how 80 this action takes place, I have demonstrated by using a device of the character of my invention that gangue carrying two minerals of substantially the same specific weight may be passed through the apparatus and one 85 mineral may be deposited in one trap and the other mineral deposited in the other trap.

From the foregoing description it will be seen that the invention provides a classifier which for its operation relies upon the combination of suitable baffles and deflectors which operate to direct and control air currents. The air currents are controlled and directed so as to first distribute the fine material introduced into the top of the shell 11 90 so that when the material has passed through the breaking device 19 there will be no lumps present. The air currents then thoroughly clean the mineral and separate it from the gangue. The air currents then carry the 100 mineral and any silt particles through the conduit 38 where the minerals may be deposited in the traps 62 according to their weights by controlling the admission of air 105 through the openings 66 or 58 into the traps. 110

As far as I am informed, the invention is new in its entirety and the different apparatus of the complete combination are also new.

I claim as my invention:

1. Apparatus for classifying comminuted material comprising a primary chamber having inlet openings for the admission of comminuted material and air, a secondary chamber, a passage connecting said chambers, means for reducing the air pressure in said 115 secondary chamber whereby a current of air will pass into said primary chamber and through said secondary chamber, said primary chamber embodying a chute through 120 which a stream of said comminuted material is adapted to pass by the action of gravity, an opening adjacent said chute communicating with the said passage whereby a current of air will be drawn through said stream of 125 material in said chute and the portion of said 130

material having the lower specific gravity will be carried into said secondary chamber, said secondary chamber embodying an upper portion so constructed as to cause the said 5 material carried by said current of air to be deposited, and a lower portion to receive the deposited material, said lower portion having adjustable openings for the admission of air, whereby an upwardly moving current 10 of air may be created to prevent the deposition of the portion of said material having the lower specific gravity.

2. In a separator, a classifying chamber 15 covered by an inclined screen, means for creating a suction within said classifying chamber, means for directing a current of air and a stream of comminuted material against the upper portion of said screen, and means for directing a current of air against said 20 screen at an angle to said first current of air in such a manner as to retard the flow of said material and agitate the same.

3. In a separator, a classifying chamber 25 covered by an inclined screen, means for creating a suction within said classifying chamber, means for directing a stream of air and comminuted material against the upper portion of said screen, and means for directing a second stream of air against said screen, 30 said last mentioned means being located below the top of said screen, whereby eddy-currents are created at the confluence of said streams to retard and agitate said material.

4. In a separator, a classifying chamber 35 having an inclined upper wall serving as a deflector and an oppositely inclined wall, an outer wall substantially parallel to said lower wall forming a channel therebetween, a baffle substantially parallel to said two walls connected at its lower end to the said lower wall 40 of said classifying chamber and dividing said channel into inner and outer passages, means for creating a suction within said inner passage, means for directing a current of air 45 and a stream of comminuted material against said deflector whereby said air and material will flow along said deflector into said channel, and means for admitting a current of air into the lower end of said outer passage, said 50 air currents being so adjusted that the lighter portion of said material will be drawn into said inner passage and the heavier portion of said material will pass into said outer passage.

5. A classifying device comprising a casing, 55 inlet means in said casing for the admission of comminuted material, air inlet means in said casing, a classifying chamber within said casing, a screen covering said chamber, means for reducing the air pressure in said 60 chamber, whereby during normal operation a current of air and a stream of said material are drawn into said casing and through said screen, said air inlet being so adjusted that the pressure in said casing is normally below 65 atmospheric pressure, a pipe leading from

said chamber and opening outside said casing, a valve in said pipe adapted to remain closed during normal operation, and to open when the pressure in said chamber is lowered, whereby any clogging of said screen by said 70 comminuted material will cause said valve to open, and the inrush of air through said pipe will clean said screen.

6. A trap for collecting comminuted material carried in suspension in a current of air 75 below atmospheric pressure, comprising a conduit through which said current of air is adapted to pass, an opening in the lower side of said conduit communicating with a collection chamber located below said conduit 80 whereby said material is adapted to pass by gravity into said chamber, air inlet means in said chamber for allowing air to flow into said chamber and upwardly through said material 85 into said conduit, said air inlet means being adjustable to control the range of specific gravity of the material deposited in said chamber.

7. A trap for collecting comminuted material carried in suspension in a current of air 90 below atmospheric pressure, comprising a conduit through which said current of air is adapted to pass, an opening in the lower side of said conduit communicating with a collection chamber located below said conduit 95 whereby said material is adapted to pass by gravity into said chamber, air inlet means in said chamber for allowing air to flow into said chamber and upwardly through said material 100 into said conduit, said air inlet means being adjustable to control the range of specific gravity of the material deposited in said chamber.

8. A trap for collecting comminuted material carried in suspension in a current of air 105 below atmospheric pressure, comprising a conduit having a horizontal portion and a vertical portion, through which said current of air is adapted to pass, an opening in the lower side of said conduit at the junction of said horizontal and vertical portions communicating with a collection chamber located 110 below said conduit, whereby said material is adapted, under the influence of gravity and inertia, to pass into said chamber, air inlet means in said chamber for allowing air to flow into said chamber and upwardly through said material 115 into said conduit, said air inlet means being adjustable to control the range of specific gravity of the material deposited in said chamber.

9. In a classifying apparatus of the character described, the combination of: a shell; 120 a breaking device; inlet means for passing a comminuted material onto said breaking device; a classifying device in said shell below said breaking device; means for placing a suction on said classifying device, said suc- 125 130

tion drawing air into said shell, said air carrying the mineral particles of said comminuted material through said classifying device; and an air inlet nozzle arranged to admit a current of air against the surface of said classifying device between said surface and said comminuted material.

10. In a classifying apparatus of the character described, the combination of: a shell; a breaking device; inlet means for passing a comminuted material onto said breaking device; a classifying device in said shell below said breaking device; means for placing a suction on said classifying device, said suction drawing air into said shell, said air carrying the mineral particles of said comminuted material through said classifying device, said air being admitted into said shell in such a manner that violent agitation takes place in said shell between said breaking device and said classifying device; and an air inlet nozzle arranged to admit a current of air against the surface of said classifying device between said surface and said comminuted material.

11. In a classifying apparatus of the character described, the combination of: a shell; a breaking device; inlet means for passing a comminuted material onto said breaking device; a classifying device in said shell below said breaking device; means for placing a suction on said classifying device, said suction drawing air into said shell, said air carrying the mineral particles of said comminuted material through said classifying device; a baffle forming a confined chamber adjacent said classifying device into which a part of said mineral not passed through said classifying device will pass; and a pipe connected to said confined chamber through which the mineral in said confined chamber is drawn, said pipe being connected to said means for placing a suction on said classifying device.

12. In a classifying apparatus of the character described, the combination of: a shell; a breaking device; inlet means for passing a comminuted material onto said breaking device; a classifying device in said shell below said breaking device; means for placing a suction on said classifying device, said suction drawing air into said shell, said air carrying the mineral particles of said comminuted material through said classifying device; a baffle forming a confined chamber adjacent said classifying device in which a part of said mineral not passed through said classifying device will pass; a pipe connected to said confined chamber through which the mineral in said confined chamber is drawn; and a trap connected to said pipe.

13. In a classifying apparatus of the character described, the combination of: a shell; a breaking device; inlet means for passing a

comminuted material onto said breaking device; a classifying device in said shell below said breaking device; means for placing a suction on said classifying device, said suction drawing air into said shell, said air carrying the mineral particles of said comminuted material through said classifying device; a baffle forming a confined chamber adjacent said classifying device into which a part of said mineral not passed through said classifying device will pass; a pipe connected to said confined chamber through which the mineral in said confined chamber is drawn, said pipe being connected to said means for placing a suction on said classifying device; and a trap connected to said pipe.

14. In a classifying apparatus, a casing, means for admitting comminuted material into said casing, a screen within said casing, for separating the coarse and fine particles of said material, means for conveying the fine particles from said casing and classifying the same according to specific gravity, and separate means for conveying the coarse particles from said casing and classifying the same according to specific gravity.

15. In a classifying apparatus, means for creating a continuous current of air, means for suspending comminuted material in said current of air, a screen for separating the coarse and fine particles of said material, a portion of said current of air passing through said screen and carrying the fine particles, and a portion of said air passing around said screen and carrying the coarse particles, and independent means for classifying said coarse and fine particles according to specific gravity.

In testimony whereof, I have hereunto set my hand at Los Angeles, California, this 23rd day of November, 1927.

HUGH H. MCKENNA.
